J. R. RENKIN, OF HILLSDALE, PENNSYLVANIA, ASSIGNOR TO HIMSELF AND M. M. GRUMBLING, OF SAME PLACE.

Letters Patent No. 95,726, dated October 12, 1869.

IMPROVEMENT IN REVERSIBLE AXLE FOR CARRIAGES.

The Schedule referred to in these Letters Patent and making part of the same.

To all whom it may concern:

Be it known that I, J. R. RENKIN, of Hillsdale, in the county of Indiana, and State of Pennsylvania, have invented a new and useful Improvement in Reversible Axles for Carriages; and I do hereby declare that the following is a full, clear, and exact description thereof, reference being had to the accompanying drawings, and to the letters of reference marked thereon.

The nature of my invention consists in constructing the axle of carriage with double and reversible spindles, with projections D, as hereinafter described.

To enable others skilled in the art to make and use my invention, I will proceed to describe its construction and operation.

In the accompanying drawings, which form part of my specification—

Figure 1 is a side view of my improvement in axles for carriages.

Figure 2 is a longitudinal section of the same at line y.

Figure 3 is a top view of the double spindle.

The axle is made in two parts, A and B, which are held together by clips C.

In the ends of the parts A and B are fitted the

double spindles e and f, the form of which is clearly shown in fig. 3.

The construction and arrangement of the several parts, and the relation they bear to each other, are clearly shown in the accompanying drawings.

My improved axle is secured to the running gear and body of the carriage in the ordinary manner.

The novelty of my improvement consists in providing the reversible spindle with the projections D, which are placed midway between the two ends of the spindle. These projections will prevent the spindle from moving endwise in the body of the axle.

In case one end of the spindle is broken off, the clips C can readily be removed, the parts A and B parted, the spindle reversed, and the several parts secured together by the clips.

What I claim as of my invention, is—

Providing the reversible spindle e f with the projections D, as herein described, and for the purpose set forth.

J. R. RENKIN.
